NONREFILLABLE BOTTLE

John William Spanyer, Louisville, Ky.

Application April 26, 1939, Serial No. 270,224

7 Claims. (Cl. 215—21)

This invention relates to a nonrefillable attachment for bottles.

The invention has for its object to provide, in a manner as hereinafter set forth an attachment of the class referred to for positioning in the neck of a bottle and having parts thereof for fixedly securing the attachment to the wall of and prevent its removal from the neck, as well as with the attachment acting to prevent the refilling of the bottle with which it is employed.

The invention has for its further object to provide an attachment for the purpose referred to capable of being wedgingly fixed within a bottle neck, and including means acting, when an attempt is made to remove the attachment surreptitiously to spread and wedge tightly against the wall of the neck thereby arresting the removal of the attachment.

A further object of the invention is to provide, in a manner as hereinafter set forth a nonrefillable attachment of the valve controlled type for securing in the neck of the bottle and with the attachment being so constructed as to prevent the tampering of the valve thereof to an extent to permit of the bottle to be surreptitiously filled.

Further objects of the invention are to provide, in a manner as hereinafter set forth, an attachment for the purpose referred to which is simple in its construction, strong, durable, compact, readily installed with respect to the neck of a bottle, thoroughly efficient in its use, and comparatively inexpensive to manufacture.

Embodying the objects aforesaid and others which may hereinafter appear, the invention consists of the novel construction, combination and arrangement of parts as will be more specifically referred to and illustrated in the accompanying drawing, wherein is shown an embodiment of the invention, but it is to be understood that changes, variations and modifications may be resorted to which fall within scope of the invention as claimed.

In the drawing:

Figure 1 is a top plan of the attachment.

Figure 2 is a vertical sectional view of the attachment showing the adaptation thereof with respect to the throat of a closed bottle neck, the latter being shown in dotted line, and

Figures 3, 4 and 5 are respectively sections of the attachment on lines 3—3, 4—4 and 5—5 Figure 2.

With reference to the drawing 1 denotes a bottle neck having a tapered throat 2. The neck 1 is shown as having its outer end closed by a removable closure 3. The neck 1, throat 2 and closure 3 are illustrated in dotted lines.

The attachment includes a combined valve seat, guide means and container forming element 4 of cylindrical contour, a combined cap, latch, outlet and spreader forming element 5 in the

form of an annulus, a combined guide and outlet passages forming element 6, a globular valve 7 and a compressible combined securing and sealing element 8 of cylindrical contour. The foregoing elements will be constructed from any suitable material, but with respect to the element 8 it preferably will consist of cork.

The element 4 comprises a cylindrical body part 9 open at each end and is formed at its inner end with an inwardly extending annular flange 10. The latter extends inwardly at right angles to the inner end of body part 9 and has its inner edge beveled to provide a valve seat 11 for the valve 7 and in this connection attention is directed to Figure 2. The inner face of the body part 9 has formed integral therewith and lengthwise thereof a series of equi-spaced valve guides 12 which are also integral at their inner ends with the upper face of the flange 10. The guides 12 are of V-shaped contour in top plan and have their apices 13 disposed inwardly adjacent to the valve seat 11. The guides 12 are of equal length and width, but of a length less than the length and have their upper ends 14 positioned below the upper end of the body part 9. The ends 14 of guides 12 align and provide seats for the guard element 6 and in this connection attention is directed to Figure 2. The upper terminal portion 15 of body part 9 is of enlarged thickness with respect to the remaining portion of the body part 9. The portion 15 is extended laterally with relation to the outer periphery of the said remaining portion of body part 9. The top edge 16 of portion 15 is squared and the outer edge 17 of portion 15 inclines inwardly from the outer end 35 of said edge 16 to the point of mergence of portion 15 with the said remaining portion of body part 9. The portion 15 constitutes a keeper for a purpose to be referred to and gradually increases in width from its upper to its lower end. 40

The element 5 comprises a body part 18 in the form of a flat annulus and an annular rim 19 integral with the outer marginal portion of the lower face of body part 18. The transverse cross sectional length of body part 45 18 is greater than the transverse cross sectional length of rim 19. The latter is of greater thickness than body part 18 and has its inner side edge 20 spaced outwardly from the inner side edge 21 of body part 18. The latter has its outer side edge 22 flush with the outer side edge 23 of rim 19. The inner side edge 20 of rim 19 inclines downwardly and inwardly throughout from the lower face of body part 18 whereby rim 19 gradually increases in thickness from its upper to 55 its lower end. The inclination of edge 20 is opposite with respect to the inclination of the edge 17 of portion 15 of body part 9. The element 5 is formed with a series of spaced equidistant vertical slits 24 which extend down 60

through the outer portion of body part 18 and entirely through the rim 19. The material freed by the slits 24 form element 5 with a series or a circular row of resilient latching members 25 for coaction with the keeper formed by the rim 19. The element 5 is positioned on the top of and it is latched to the element 4 by the coaction of the members 25 with the inclined edge 17. The element 5 is snapped over the portion 15 of element 4 and the coaction of the edges 17 and 20 secure elements 4 and 5 together. The body part 18 extends inwardly from the edge 16 of body part 9 when elements 4 and 5 are secured together. The opening formed in body part 18, due to the fact that the latter is in the form of an annulus constitutes the outlet for the contents of the bottle with which the attachment is connected.

The element 6 comprises a flat circular disc-like body part 26 of materially less diameter than the inner diameter of element 4 and which constitutes a guard. Extended from the edge of body part 26 is a series of radially disposed equidistant spaced combined supporting and retaining members 27 of angular form corresponding in number to the number of the valve guides 12. The members 27 are of like form and each consists of a horizontal leg 28 and a vertical leg 29 merging at its lower end into the outer end of the leg 28. The latter provides a support or suspension for body part 26. The leg 29 constitutes a retainer for body part 26. The legs 28 are mounted on the upper ends 14 of the guides 12. The legs 29 bear against the inner face of body part 9 of element 4 and the lower face of body part 18 of element 5. When the latter is secured to element 4 it prevents the shifting of the element 6 lengthwise with respect to element 4 and fixedly secures, in connection with the guides 12 element 6 in element 4. The spaces between the members 27 formed outlet passages or channels for the contents of the bottle with which the attachment is secured to, when the bottle is tilted for the purpose of removing the valve 7 from off of its seat provided by the inner edge 11 of the flange 10. The diameter of the valve 7 with respect to its seat is such as to prevent the valve from passing inwardly from the attachment through the valve seat.

The element 8 comprising a sleeve or collar 30 of compressible material, open at each end having its inner diameter uniform and its outer diameter gradually increasing from each of its ends to its diametric center. The sleeve 30 is of less length than element 4 and is disposed in tightly encompassing relation with respect to the outer face of body part 9 of said element 4 from the lower end of rim of element 5 to the lower end of element 4.

The attachment will require but one additional operation in bottling and which is the positioning of the attachment within the throat of the bottle neck at a point spaced a substantial distance below the bottle mouth. After the attachment has been positioned as aforesaid the cork or screw cap is placed as usual.

The outer diameter of the element 8 is such with respect to the diameter of the bottle throat to provide for element 8 being compressed when the attachment is disposed within the bottle neck. The element 8 thereby provides a snug fit for the attachment relative to the bottle throat and fixedly secures the attachment stationary, under normal conditions relative to the bottle neck. The throat of the bottle should taper to a smaller diameter to prevent the attachment from

being pushed down into the body of the bottle. The element 8 provides a liquid seal therebetween and the throat of the bottle.

The latching members 25, after the assembly has once been inserted in the bottle neck prevent the removal thereof, as if an attempt is made to remove the assembly any outward pull on element 5 will spread said members 25 causing the rim of element 5 to spread and wedge tightly against the inner face of the bottle neck thereby locking the assembly to arrest removal thereof.

The edges 17 and 20 are oppositely bevelled at ninety degrees.

What I claim is:

1. A nonrefillable attachment for bottles and for positioning in the tapered neck of a bottle, said attachment comprising a combined valve seat, guide means and container forming element of cylindrical form having means on its outer face to constitute a keeper at its upper end formed with an inwardly beveled outer surface, a shiftable valve retained in and by said element, a combined guard and outlet passages forming means mounted in and supported by said element at said end of the latter, a combined cap, latch, outlet and spreader forming element in the form of an annulus bearing on said means and provided with an annular row of separate extendible latching members having complementary inner surfaces coacting with the beveled surface of said keeper for securing said elements together and for coaction with the wall of the bottle neck to prevent the outward removal of the attachment, and a compressible combined securing and sealing means of cylindrical form encompassing said first mentioned element and coacting with the wall of the bottle neck to provide a liquid seal and to wedgingly secure the attachment stationary within the neck of the bottle.

2. A nonrefillable attachment for bottles and for positioning in the tapered neck of a bottle, said attachment comprising a combined valve seat, guide means and container forming element of cylindrical form having means on its outer face to constitute a keeper at its upper end formed with an inwardly beveled outer surface, a shiftable valve retained in and by said element, a combined guard and outlet passages forming means mounted in and supported by said element at said end of the latter, a combined cap, latch, outlet and spreader forming element in the form of an annulus bearing on said means and provided with an annular row of separate extendible latching members having complementary inner surfaces coacting with the beveled surface of said keeper for securing said elements together and for coaction with the wall of the bottle neck to prevent the outward removal of the attachment, a compressible combined securing and sealing means of cylindrical form encompassing said first mentioned element and coacting with the wall of the bottle neck to provide a liquid seal and to wedgingly secure the attachment stationary within the neck of the bottle, said first mentioned element being formed therein and lengthwise thereof with spaced valve guides, and said guard means including spaced combined supports and retainers seated on said guides at one end of the latter and bearing against the second mentioned element.

3. A nonrefillable attachment for bottles and for positioning in the tapered neck of a bottle, said attachment comprising a combined valve seat, guide means and container forming element of cylindrical form having means on its outer

face to constitute a keeper at its upper end formed with an inwardly beveled outer surface, a shiftable valve retained in and by said element, a combined guard and outlet passages forming means mounted in and supported by said element at said end of the latter, a combined cap, latch, outlet and spreader forming element in the form of an annulus bearing on said means and provided with an annular row of separate extendible latching members having complemental inner surfaces coacting with the beveled surface of said keeper for securing said elements together and for coaction with the wall of the bottle neck to prevent the outward removal of the attachment, a compressible combined securing and sealing means of cylindrical form encompassing said first mentioned element and coacting with the wall of the bottle neck to provide a liquid seal and to wedgingly secure the attachment stationary within the neck of the bottle, said first mentioned element being formed at one end with a seat for said valve and therein lengthwise thereof with spaced guides of less length than the length of such element, said guides bearing at one end against the lower face of the said combined guide and outlet passages forming means.

4. A nonrefillable attachment for bottles and for positioning in the tapered neck of a bottle, said attachment comprising a combined valve seat, guide means and container forming element of cylindrical form having means on its outer face to constitute a keeper at its upper end formed with an inwardly beveled outer surface, a shiftable valve retained in and by said element, a combined guard and outlet passages forming means being in the form of a disc of less diameter than the inner diameter of the first mentioned element formed with spaced radially disposed combined supporting and retaining members bearing against the said elements.

5. A nonrefillable attachment for bottles and for positioning in the tapered neck of a bottle, said attachment comprising a combined valve seat, guide means and container forming element of cylindrical form having means on its outer face to constitute a keeper at its upper end formed with an inwardly beveled outer surface, a shiftable valve retained in and by said element, a combined guard and outlet passages forming means mounted in and supported by said element at said end of the latter, a combined cap, latch, outlet and spreader forming element in the form of an annulus bearing on said means and provided with an annular row of separate extendible latching members having complemental inner surfaces coacting with the beveled surface of said keeper for securing said elements together and for coaction with the wall of the bottle neck to prevent the outward removal of the attachment, a compressible combined securing and sealing means of cylindrical form encompassing said first mentioned element and coacting with the wall of the bottle neck to provide a liquid seal and to wedgingly secure the attachment stationary within the neck of the bottle, said first mentioned element being formed at one end with a seat for said valve and therein lengthwise thereof with spaced guides of less length than the length of such element, said guides bearing at one end against the lower face of the said combined guide and outlet passages forming means, said guides being of V-form and having their apices disposed inwardly adjacent to said valve seat.

6. A nonrefillable attachment for bottles and for positioning in the tapered neck of a bottle, said attachment comprising a combined valve seat, guide means and container forming element of cylindrical form having means on its outer face to constitute a keeper at its upper end formed with an inwardly beveled outer surface, a shiftable valve retained in and by said element, a combined guard and outlet passages forming means mounted in and supported by said element at said end of the latter, a combined cap, latch, outlet and spreader forming element in the form of an annulus bearing on said means and provided with an annular row of separate extendible latching members having outwardly beveled inner surfaces coacting with the beveled surface of said keeper for securing said elements together and for coaction with the wall of the bottle neck to prevent the outside removal of the attachment, said attachment coacting with the wall of the bottle neck to provide a liquid seal and wedgingly secured stationary within the neck of the bottle.

keeper for securing said elements together and for coaction with the wall of the bottle neck to prevent the outward removal of the attachment, a compressible combined securing and sealing means of cylindrical form encompassing said first mentioned element and coacting with the wall of the bottle neck to provide a liquid seal and to wedgingly secure the attachment stationary within the neck of the bottle, said first mentioned element being formed at one end with a seat for said valve and therein lengthwise thereof with spaced guides of less length than the length of such element, said guides bearing at one end against the lower face of the said combined guide and outlet passages forming means.

7. In a nonrefillable bottle attachment for positioning in the tapered neck of a bottle, a combined valve seat, guide means and container forming element of cylindrical form having means to constitute a keeper at its upper end formed with an inwardly beveled outer surface, a shiftable valve retained in and by said element, a combined guide and outlet passages forming means mounted in and supported by said element at said end of the latter, a combined cap, latched outlet and spreader forming element in the form of an annulus bearing on said means and provided with an annular row of separate extendible latching members having outwardly beveled inner surfaces coacting with the beveled surface of said keeper for securing said elements together and for coaction with the wall of the bottle neck to prevent the outside removal of the attachment, said attachment coacting with the wall of the bottle neck to provide a liquid seal and wedgingly secured stationary within the neck of the bottle.
